UNITED STATES PATENT OFFICE.

JAMES A. PORTER, OF NEVADA, IOWA.

ROTARY ENGINE.

SPECIFICATION forming part of Letters Patent No. 654,119, dated July 17, 1900.

Application filed June 12, 1899. Serial No. 720,168. (No model.)

To all whom it may concern:

Be it known that I, JAMES A. PORTER, a citizen of the United States, residing at Nevada, in the county of Story and State of Iowa, 5 have invented a new and useful Improvement in Rotary Engines, of which the following is a specification.

One object of this invention is to provide a rotary engine of simple, strong, and durable construction that may be readily and easily reversed and that may when the engine is in any position be started by manipulation of a steam-valve.

A further object is to provide means where- 15 by the expansion of the steam may be utilized to its maximum capacity in driving the rotary piston.

A further object is to provide means where- 20 by the engine may be readily and quickly re- versed without interfering with the operation of the automatic cut-off; and my object is, fur- ther, to provide means whereby steam is ad- mitted to the steam-chamber gradually and 25 when the pistons have passed the point where the effective stroke ends the steam will be exhausted in such a manner that there can be no back pressure upon the piston.

My invention consists in certain details in 30 the construction, arrangement, and combi- nation of the various features of the device whereby the objects contemplated are at- tained, as hereinafter more fully set forth, pointed out in my claims, and illustrated in 35 the accompanying drawings, in which—

Figure 1 shows a vertical transverse sec- 40 tional view taken through the indicated line 1 1 of Fig. 2, and Fig. 2 is a vertical central sectional view in a right-angled position relative to Fig. 1.

Referring to the accompanying drawings, 45 the reference-numeral 10 is used to indicate the cylinder proper, having the heads 11, bolted thereto. The shaft 12 is mounted in the heads eccentrically, and formed on the inner 50 face of the heads are the circular grooves 13, which are arranged concentrically of the heads themselves and eccentrically relative to the shaft. At the upper end of this cylinder are two steam-chambers 14, in which 55 valves are mounted which will be hereinafter described. Steam-passages 15 extend from these chambers 14 around the interior of the

cylinder a distance of about one-third of the circumference of the same on both sides. These passages 15 on each side of the engine 55 communicate with the chambers 14, and I have provided a number of openings 16, leading from the steam-passages 15 to the interior of the cylinder at suitable distances of separation, and 17 indicates small openings 60 leading from the said passage 15 to the interior of the cylinder, near the upper end thereof. These are for the purpose of permitting the steam to exhaust, so that there can be no back pressure. 65

The reference-numerals 18 indicate valves placed in the openings 14 and having their stems 19 extended to opposite sides of the engine. These valves are arranged to direct the steam from the inflow-pipe at their tops to 70 discharge through either one of the passages 15, and they are connected in such a manner that when one valve is placed in position to conduct the steam to the passage on one side the opposite valve will permit the steam to 75 exhaust by means of the cranks 20, fixed to the valve-stems and having the links connected therewith and also pivotally connected with a lever 21, which lever is pivoted at its central portion to a support 22, fixed to the 80 engine-casing near its central portion. Hence when one valve is turned in one direction the other valve will turn in the opposite direction by the manipulation of a single lever.

The reference-numeral 23 is used to indi- 85 cate a steam-chest on top of the engine and having a passage 24 to communicate with one of the openings 14, and 25 indicates a pipe to serve as an exhaust leading from the opposite one of the openings 14. Within this 90 steam-chest 23 a slide-valve 26 is mounted to serve as a cut-off between the induction-pipe 27 and the passage 24. A rod 28 is connected with this cut-off valve 26 and extends out- 95 wardly through a packing 29 to connect with the lever 30, which lever in turn is fulcrumed near its central portion by a bracket 31 and is provided with an antifriction-roller 32 at its lower end.

33 indicates a wheel fixed to the shaft 12 100 and having formed thereon a cam-groove 34, in which the said roller 32 is placed. This cam-groove is so arranged and proportioned relative to the other parts of the machine that

when the steam-chamber of the engine has been in position to receive steam during a certain part of its stroke the valve 26 will be shut, so that the expansive force of the steam 5 will be utilized throughout the remainder of the stroke.

I have provided means whereby in the event that the engine is stopped when the valve 26 is in its closed position steam may 10 be admitted to the interior of the steam-chamber, so that the engine may be started by means of the steam-pressure alone. This means comprises a pipe 35, communicating at one end with the inflow-pipe 27 and at its 15 other end with the steam-chamber 24, below the valve 26, and a cut-off valve 36 is placed in this pipe 35. Hence when it is desired to start the engine under the above conditions all that is necessary is to open the valve 26 20 and then close the same as soon as the engine has started to rotate and obtained a sufficient momentum.

The reference-numeral 37 is used to indicate a hub fixed concentrically to the shaft 12 25 and having therein a number of radial grooves 38. In these grooves 38 the flat pistons 39 are slidingly mounted, and these pistons 39 are provided with antifriction-rollers 40 to project outwardly therefrom and to enter the 30 grooves 13. By this means the pistons 39 are constantly held to their outer limits, or, rather, in direct contact with the interior of the cylinder at all times, and said pistons are located at such a distance of separation that 35 the steam will not begin to exhaust through one of the openings 16 until the next adjoining piston has passed the opening 16 on the opposite side.

In practical operation it is obvious that the 40 engine may be readily and quickly reversed, the supply of steam be automatically cut off, so that the expansive force may act during a part of its effective stroke, and the engine started when the valve 26 is closed; and it is obvious, 45 further, that a certain amount of steam would be admitted into the steam-chamber during the time that the piston 39 passes each of the openings 16, and, furthermore, that when the piston has passed the first opening 16 of the 50 exhaust side the steam will be exhausted gradually from the steam-chamber and any steam that might be retained in the chamber will be exhausted through the small openings

17, so that no back pressure may be applied to the pistons 39.

Having thus described the invention, what I claim as new therein, and desire to secure by Letters Patent of the United States therefor, is—

1. In a rotary engine, the combination of a cylinder, a hub rotatably mounted within the cylinder, sliding pistons in the hub, steam-passages for admitting steam to and exhausting steam from the cylinder at proper points, two valves mounted in the cylinder, the one 60 connected with the inflow and the other with the exhaust pipe, means for operating the said valves in unison to move in opposite directions to reverse the engine, a slide-valve connected with the engine above the aforesaid valves, a pipe leading from the induction-pipe to the engine at a point above the said slide-valve and means for automatically operating it to cut off at a certain predetermined point, substantially as and for the purposes 70 stated.

2. A rotary engine, comprising in combination, a cylinder 10, cylinder-heads 11 fixed thereto and having grooves 13 therein, a shaft 12 eccentrically mounted within the engine 80 and having a wheel 33 fixed thereto provided with a cam-groove 34, a hub 37 fixed to the said shaft, a series of pistons 39 slidingly mounted in said hub, rollers 40 connected with the said pistons to operate within the 85 grooves 13, steam-passages 15 and openings 16 and 17 leading therefrom to the interior of the cylinder, valves 18 at the top of the engine, and means for reversing same, a steam-chamber at the top of the engine, an inflow-pipe 90 leading thereto, a slide-valve mounted in said steam-chamber, a stem connected with said slide-valve, and a lever pivoted to a suitable support and connected at one end to the said stem and having its other end inserted in the 95 cam-groove 34, a pipe connected with the inflow-pipe and extending around the said valve, a cut-off valve in said pipe and an exhaust-pipe 25, all arranged and combined substantially in the manner set forth and for the purposes 100 stated.

JAMES A. PORTER.
